SAFETY DEVICE FOR DIESEL AND INTERNAL-COMBUSTION ENGINES

Filed May 26, 1947

UNITED STATES PATENT OFFICE

2,603,690

SAFETY DEVICE FOR DIESEL AND INTERNAL-COMBUSTION ENGINES

Thomas J. Moody, Louisville, Ky., assignor to
Robertshaw-Fulton Controls Company, a corporation of Delaware

Application May 26, 1947, Serial No. 750,412

4 Claims. (Cl. 175—320)

1

This invention relates to safety devices, and more particularly to safety devices for internal combustion engines. While the invention possesses particular utility in its application as a safety device to diesel engines, the invention is not restricted thereto, as will appear from the following disclosure, as the controlled element, for example, may be in the ignition circuit of an internal combustion engine of other than the diesel type, while other applications of the invention will be apparent to those skilled in the art.

Taking a diesel engine for purposes of exemplifying the invention, it has heretofore been proposed to provide such an engine with pressure-controlled or thermostatically-controlled means for stopping the engine in the event of abnormally low oil pressure or abnormally high oil or water temperatures, but devices of this character have had the grave objection that they add materially to the complexity or the bulk, or both, of the accessory installation. The present invention avoids the foregoing difficulty by utilizing means to close a switch upon the occurrence of abnormally low lubricating oil pressure or abnormally high oil or jacket temperatures to energize a solenoid which cuts off the fuel supply, as by means of a valve in the fuel line or by stoppage of the injection pump. In devices of this character, as will be apparent, the switch in the solenoid circuit must be opened when the engine is started because otherwise it would be impossible to start the engine as long as the solenoid circuit is closed to hold the control element in position for preventing operation of the engine. The operator, once the engine is in operation, is then supposed to close the manually operated switch in the solenoid circuit so as to condition the safety device for operation upon occurrence of the condition of danger, but if the operator forgets to close this switch, as after the oil pressure has come up to normal, the safety device is not in condition for operation and the subsequent lowering of the oil pressure or the occurrence of abnormally high oil or jacket temperatures will not energize the safety device to stop the engine.

It is the primary object of the present invention to provide a safety device of the type just characterized which is entirely safe because the operator is relieved of the responsibility of closing the switch through the solenoid after the engine is started.

2

A further object of the present invention is to provide a safety device of the character referred to wherein the circuit through the solenoid is automatically established when the engine is started.

Another object of this invention is to provide a safety device as characterized in which the circuit through the solenoid is closed only after a predetermined period of operation.

Another object of this invention is to provide a safety device as characterized which employs a time-delay switch that operates automatically when the engine is started.

Another object of this invention is to provide a safety device of the type characterized which employs a time-delay switch whose circuit is opened automatically when the circuit of the safety device is properly conditioned for normal operation.

Another object of this invention is to provide a safety device of the type characterized which may be used with solenoid valves or injection pump racks of the character now conventionally used in diesel engines and therefore with a minimum of alteration in the installations as now provided.

Another object of this invention is to provide a safety device of the type characterized which is certain in operation, and which also assures an adequate time delay before coming into operation so as to avoid premature actuation of the safety device.

Another object of this invention is to provide a safety device of the type characterized which though called into action permits the engine to be started again and operated for a limited period of time, so that, for example, if a vehicle operated by an engine provided with such a safety device should be stopped in a hazardous position by the safety device coming into action the engine may be briefly operated to enable the vehicle moving out of such position.

Another object of this invention is to provide a device of the type characterized which is simple and compact in construction and inexpensive to install and maintain.

Other objects will appear as the description of the invention proceeds.

The invention is capable of receiving a variety of mechanical expressions, one of which is illustrated diagrammatically, so as to facilitate an un-

derstanding of its principle of operation, on the accompanying drawing, but it is to be expressly understood that the drawing is for purposes of illustration only, and is not to be construed as a definition of the limits of the invention, reference being had to the appended claims for that purpose.

Referring in detail to the drawing, a schematic view illustrates diagrammatically a circuit arrangement embodying the present invention.

As illustrated, 10 designates any suitable solenoid in circuit with battery 11, although any other suitable electromagnetic device may be used in place of a solenoid as will be apparent to those skilled in the art. A manually operable switch 12 is in circuit with the solenoid and battery, and operatively connected with the core or armature 13 of the solenoid is a member 14 for controlling the operation of the engine and which may take a variety of forms, as a valve in the fuel line or a rack on an injection pump, so that when the solenoid is inoperative the fuel valve is open or the injection pump is operative to supply fuel, but when the solenoid is operated the valve is closed or the rack operates a valve of the injection pump to close the same and discontinue the operation of the pump. In place of a fuel valve or rack on the injection pump, the member to be controlled can equally well be a member, as a switch, in the ignition system of an engine. When a solenoid valve is used the valve may be any of the well-known solenoid valves now conventionally used in the fuel line of a diesel engine. When a rack on the injection pump is used the construction employed may be any of those now used for controlling the operation of the injection pump.

Connected at 15 to one of the leads 16 of the solenoid 10 is a conductor 17 leading to the contact point 18 of a switch 19. Switch 19 is associated in any suitable way with means responsive to pressure, or to temperature, or to both, for closing the switch 19 when a dangerous condition arises, as an undue drop in the pressure of the oil, or an undue rise in temperature of the cooling water or the oil, etc. As shown, a pressure responsive member 20, here shown as in the form of an expansible and contractible corrugated tubular metal container or bellows, has its interior connected with any suitable source of oil pressure, as the primary oil filter, so as to be responsive to the oil pressure developed by the oil pump. Bellows 20 is connected to the switch 19 in any suitable way, as by a link diagrammatically indicated at 21. As here shown, the switch 19, or a second switch connected into the circuit in parallel therewith is also adapted to be operated by a rise of temperature, and to this end any suitable thermostatic bulb 22, which may be subjected to the temperature of the water in the water jacket or any other suitable part of the water line or to the temperature of the oil, etc., is suitably connected, as by conduit 23, to an expansible and contractible corrugated tubular metal container or bellows 24 having a thrust element 25 which may engage and operate the switch 19 or a second switch element connected in parallel thereto.

Switch 19 is connected by conductor 26 to a multiple switch operable by any suitable relay coil 27. As illustrated diagrammatically, three contacts 28, 29 and 30, respectively, are positioned for contact with elements 31, 32 and 33 carried by armature 34 and suitably insulated from each other. Element 33 is connected with

conductor 26 and contact 30 is connected by conductor 35 with a connection 36 in the circuit of the solenoid but on the battery side of the switch 12 opposite from the connection 15. Element 32 is connected with the coil 27 by lead 37, and also by conductor 38 with the contact element 39 of a time-delay switch composed of a bimetallic strip 40 and a heater coil 41. Bimetallic strip 40 is connected to the contact elements 28 and 29 by conductors 42 and 43. Heater coil 41 is connected through conductor 44 with element 31 and through conductor 45 with the negative terminal of the generator by conductor 46, the positive terminal of said generator being connected to the conductors 42, 43 through conductor 47. Conductor 45 is also connected to the relay coil 27 through conductor 48. It is to be understood that contact elements 31, 32 and 33 move together as a unit in response to operation of the armature 34 by relay coil 27.

As indicated in the drawing, the connections to the generator circuit must be made at some point between the generator armature terminals and the generator cutout relay. The circuit through which the battery 11 is normally charged is completed by a conductor 50 from the left-hand end of the solenoid 10 to conductor 46 which is the negative side of the battery 11. The positive side of the battery 11 is connected to the stationary contact 52 of the cut-out relay by conductor 51 to conductor 35. Since the remaining connections of the cut-out relay are conventional further description is deemed unnecessary. This connection is necessary in order to prevent any potential being impressed on the circuit of the safety device until the engine is actually in operation. As the generator cutout relay disconnects the generator from the battery circuit until the generator potential is equal to or greater than the battery potential, no potential is impressed on the circuit above described until the engine is actually in operation.

When the engine is at rest the oil pressure in the bellows 20 is at zero and the bellows 20 is thus in its contracted position, holding the switch 19 closed. Similarly, the temperature to which the bulb 22 is subjected is insufficient to expand the bellows 24 and the thrust element 25 is out of contact with the switch 19. Also, the relay coil 27 is deenergized and the armature thereof holds the contact elements 31, 32 and 33 in the position shown in the drawing, i. e., with contact 28 closing the circuit through element 31 and contacts 29 and 30 out of engagement with the elements 32 and 33, respectively. In this relationship of the parts and assuming switch 12 is open, the engine may be started because the circuit through the solenoid is open, and therefore the solenoid valve or the rack controlled valve is open to permit flow of fuel to the engine, because the battery 11 is disconnected from the solenoid at the contact 30 and the generator is disconnected from the solenoid at the contact 29. The circuit through the heater coil 41 is closed, however, at contact 28 for energization as soon as the generator comes into operation.

When the engine is started the generator impresses a potential on the circuit of the heater coil, causing current to flow through conductor 47, contact 28, element 31, conductor 44, heater coil 41 and conductor 45, but no current will flow through the relay because contact 39 in the circuit of the relay is out of contact with the bimetallic strip 40. After a lapse of a predetermined period of operation of the heater coil 41,

say one minute, bimetallic strip 40 will have been sufficiently heated by the heater coil 41 to cause it to bend into engagement with the contact 39. This closure of the circuit at 39, 40 causes current to flow through conductor 41, conductor 42, bimetallic strip 40, contact 39, conductor 38, conductor 37, relay coil 27 and conductor 48. The energizing of the relay coil 27 operates the armature thereof to move element 31 out of engagement with contact 28 and to move elements 32 and 33 respectively into engagement with the contacts 29 and 30. The opening of the circuit at 28 discontinues the operation of the heater coil, but current now flows through conductor 47, contact 29, conductor 37, relay coil 27 and conductor 48, thereby maintaining the circuit through the relay coil, while the solenoid 10 has now been placed in circuit with the battery 11 and the switch 19 through closure of the circuit at 29, 32 and at 30, 33. This is the normal running position for the device.

During the interval of time introduced by the time-delay switch 39, 40, if the engine operates normally, oil pressure has been sufficiently developed in the bellows 20 to open the circuit of the solenoid through switch 19, and thus the solenoid is out of operation to permit the normal running of the engine. In the event the oil pressure drops below a predetermined amount, or in the event the temperature to which the bulb 22 is subjected rises a predetermined amount, bellows 20 will contract to close switch 19 or bellows 24 will be expanded to close switch 19, thereby closing the circuit through the solenoid 10. Energization of the solenoid 10 or other electromagnetic control element effects the operation of the solenoid valve to stop the flow of fuel to the engine, or if the core of the solenoid is connected to a rack operatively connected to a valve on the pump, such valve is closed so as to stop the pump supplying fuel to the engine, or opens a switch in the ignition circuit, or otherwise effects its control function. In any event, the engine is at once stopped upon the occurrence of the decrease in oil pressure or rise in temperature which should bring the safety device into operation.

It will be observed that the operation of the safety device is thus not dependent upon the closure of the switch 12, because the circuit of the solenoid 10 is properly conditioned by the actuation of the relay 27 after a predetermined interval of operation of the engine during which the switch 19 is opened if the engine is operating normally. Also, as will be apparent, if the oil pressure is not established when the engine is first started, the switch 19 is not opened and hence after the predetermined interval controlled by the time-delay switch 39, 40 the relay coil 27 is energized to move the contact elements 31, 32 and 33 from the position shown in the drawing and the solenoid will be energized to discontinue the operation of the engine before injury to the engine occurs. Furthermore, the foregoing manner of operation permits the engine to operate for a brief period of time even though the conditions exist for calling the safety device into operation, so that for example if a vehicle operated by an engine provided with the safety device should be stopped by the operation of the safety device in a position to obstruct traffic on a railroad track or in other hazardous or undesirable position the engine may be temporarily restarted and operated briefly sufficiently to move the vehicle to another position.

It will therefore be perceived that the present invention provides a safety device of the character under consideration which in no way depends for its operativeness upon the manual closing of a switch which must first be opened in order for the safety device to be temporarily thrown out of operation in order to permit the engine to start. The safety device is thus entirely automatic in operation, and assures the stopping of the engine promptly after starting, for example, if the oil pressure fails to develop, and the prompt stopping of the engine whenever thereafter by reason of a drop in oil pressure or an increase in temperature a dangerous condition arises. The automatic provision thus introduced is relatively simple and compact in structure, adding little to the complexity or bulk of the installation, while it is simple, efficient and certain in operation. It may also be readily installed for cooperation with engine controlling means already in use.

The automatic device thus provided can be made responsive to any change in pressure or temperature from which actuation is desired, those hereinbefore referred to being taken as typical only, and the solenoid or other electromagnetic control can be applied to any suitable controlling member whose operation will stop the engine, the solenoid valve, solenoid operated rack on an injection pump, etc., being taken as typical only.

While the embodiment of the invention diagrammatically illustrated on the drawing has been described with considerable particularity, it is to be expressly understood that the invention is not restricted thereto, as the invention can receive a variety of expressions, as will now be apparent to those skilled in the art, while changes may be made in details of circuit arrangement, mechanical and electrical elements employed, etc., without departing from the spirit of this invention. Reference is therefore to be had to the appended claims for a definition of said invention.

45 What is claimed is:

1. An electrically operable control device comprising a control circuit including a condition responsive switch movable between controlling positions, a normally open second switch in series circuit with the first said switch and movable to closed position for conditioning said control circuit for a controlling operation, a relay having a coil and an armature operable for closing said second switch upon energization of said coil, a normally open third switch in series circuit with said coil, and means operably associated with said third switch for effecting time delayed movement thereof to closed position, said last means including operating means connected in parallel circuit with said third switch for initiating said time delayed movement and causing energization of said coil upon expiration of a predetermined period.

2. An electrically operable control device as claimed in claim 1 wherein a normally open fourth switch is connected in circuit with said coil and is operable by said armature for maintaining said coil energized independently of the position of said third switch.

70 3. An electrically operable control device as claimed in claim 2 wherein said parallel circuit includes a normally closed fifth switch in series with said operating means and being operable by said armature to open said parallel circuit upon energization of said coil.

4. An electrically operable control device as claimed in claim 3 wherein said means operably associated with said third switch includes a bimetallic element, said operating means comprising a heater coil for said element.
